UNITED STATES PATENT OFFICE.

LOUIS A. SHEPARD, OF BROOKLYN, NEW YORK, ASSIGNOR TO CORNELIUS VANDERBILT, OF NEW YORK, N. Y.

BRAKE-BEAM.

SPECIFICATION forming part of Letters Patent No. 727,219, dated May 5, 1903.

Application filed September 9, 1902. Serial No. 122,672. (No model.)

To all whom it may concern:

Be it known that I, LOUIS A. SHEPARD, a citizen of the United States, and a resident of the borough of Brooklyn, city and State of New York, have invented certain new and useful Improvements in Brake-Beams, of which the following is a specification.

My invention relates to an improved form of brake-beam; and it consists in the features hereinafter described and claimed.

It has for its object the production of a brake-beam which may be cheaply and easily constructed and which combines great strength with lightness.

In the drawings which accompany this specification, Figure 1 is a plan, and Fig. 2 is a front view, of a brake-beam embodying my invention. Fig. 3 is a transverse section taken just outside the brake-shoe and looking toward the end of the beam.

The brake-beam is a truss the compression member of which is a hollow tube 1, preferably circular in cross-section. The tension member is a trough-shaped body 2, preferably a half-tube, as shown, and may be formed by splitting a tube longitudinally. The curvature of the concave or inner surface of the part 2 is the same as the curvature of the outer surface of the tube 1. The ends of the tube 1 are fitted or sleeved within the ends of the half-tube 2, a snug fit being obtained by reason of the curvatures of the contacting surfaces being the same. The tension member is preferably bent at its center and extends in straight lines therefrom to its ends. The ends of the compression member are bent into parallelism with the ends of the tension member, as shown, thus forming a very strong truss, since the tensional stresses which exist at any time in the tension member are resisted by the ends of the compression member in the direction of their length. The ends of the truss are much less readily bent or broken in use when of the shape shown than if the ends of the compression members were straight.

The brake-shoes 3 are sleeved upon the ends of the members 1 and 2, filling-blocks 4 being placed about that portion of the ends of the tube 1 opposite that covered by the member 2. (See Fig. 3.) The whole is then firmly united by bolts or rivets 5, passing through the parts 1, 2, 3, and 4.

A central strut 6 is provided between the members 1 and 2, which may also be used as the fulcrum for the attachment of the brake-lever. This strut is formed of a block 7, which is sleeved or otherwise fitted upon the tube 1, a block 8 fitted within the concave surface of the half-tube 2, and plates 9 secured to said blocks by rivets 10. The plates 9 are perforated at 11 for the attachment of the brake-lever.

Various minor changes may be made in the structure illustrated without departing from the spirit of my invention, the scope of which is defined by the following claims.

I claim—

1. A trussed brake-beam comprising a tubular compression member, a trough-like tension member and a strut, the ends of said compression member being parallel to the ends of the tension member and being sleeved therein, substantially as described.

2. A trussed brake-beam comprising a tubular compression member, a trough-like tension member and a strut, said tension member being bent at its center and extending therefrom in straight lines to the ends of the beam, the ends of the compression member being bent parallel to the tension-member ends and being sleeved therein, substantially as described.

3. A trussed brake-beam comprising a tubular compression member, a trough-like tension member and a strut, the ends of said compression member being parallel to the ends of the tension member and being sleeved therein, and shoes sleeved upon and secured to the united ends of said compression and tension members, substantially as described.

4. In a trussed brake-beam, a compression member, a block 7 fitted thereon, a trough-like tension member, a block 8 fitted within its concave surface, and plates 9 uniting said blocks and forming a strut, substantially as described.

In witness whereof I have hereunto set my hand this 8th day of September, 1902.

LOUIS A. SHEPARD.

In presence of—

WILLIAM KENT AUCHINCLOSS,
JAMES J. COSGROVE.
